UNITED STATES PATENT OFFICE.

WILLIAM J. WHITE, OF SAN FRANCISCO, CALIFORNIA, ASSIGNOR OF ONE-HALF TO
WILLIAM H. GILBERT, OF SAN FRANCISCO, CALIFORNIA.

PENCIL HOLDER.

Application filed January 2, 1924. Serial No. 683,897.

To all whom it may concern:

Be it known that I, WILLIAM J. WHITE, a citizen of the United States, residing at San Francisco, in the county of San Francisco and State of California, have invented new and useful Improvements in Pencil Holders, of which the following is a specification.

This invention relates to improvements in pencil holders of the type exemplified in my application for U. S. Letters Patent filed Feb. 5, 1923, Serial No. 616,983, and resides in the provision of a small, compact and simply constructed holder which provides for a more positive and reliable holding of the pencil in place while permitting of an easier and quicker mounting of a pencil in the holder than is possible with other types of pencil holders of which I am aware.

One of the objects of the invention is to provide a pencil holder of the character described wherein the pencil may be moved laterally into the holder and held therein after having been inserted in the pocket, thus doing away with the aiming of the pencil and necessity of carefully watching the movement thereof in order to insert it in place as is required with other types of holders.

Another object is to provide a holder having a specially constructed means for locking the pencil against lateral or sidewise movement out of the holder, which means does not interfere with the quick mounting of the pencil in place or interfere with the upward withdrawal of the pencil.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

Referring to the drawing:

Fig. 1 represents a fragmentary front elevation of a pocket showing attached thereto, with a pencil held therein, the holder of the invention, the pencil being shown in dotted lines in a position from which it may be

moved laterally in the pocket in order to engage in the holder.

Fig. 2 represents a top front elevation of the holder.

Fig. 3 represents a rear elevation of the holder.

Fig. 4 represents a side elevation of the holder.

Fig. 5 represents a top plan view of the holder.

Fig. 6 represents a top plan view of the blank from which the holder is formed.

The holder is constructed from a single piece of thin resilient sheet metal stamped into the blank form shown in Fig. 6, and then bent as will be herein described to provide the special construction of the invention.

The blank comprises essentially an elongated strip 1, having projecting from a point near but spaced from one end thereof, lateral portions 2 and 3 of which the latter is longer and on its free edge is provided with teeth 4. The strip 1 is doubled intermediate of its ends, that is, bent back upon itself, to provide spaced parallel jaws 5 and 6, the one 5 being shorter than the one 6 and having the teeth 4 on the free end thereof bent substantially right angularly and extended towards the jaw 6. The bend in the strip 1 is formed so that the lateral portions 2 and 3 are disposed near but spaced slightly below the upper end of the jaws. The projection 3 is bent back upon itself so as to extend preferably across the jaw 6 in spaced substantially parallel relation thereto and in the same relation to the projection 2, said member being curved where bent. This provides a substantially U-shaped clip for the pencil, which clip opens on the side of the holder and permits of a lateral insertion of a pencil into the clip from a position, for example, as shown in dotted lines in Fig. 1. The slight downward spacing of the portions 2 and 3 from the upper end of the jaws 5 and 6 provides for concealing of the portions below the upper edge of the pocket A, shown in Fig. 1.

In the projection 3, the metal between the longitudinal edges is struck out to form a clamping tongue 7, the free end of which is disposed adjacent the inner end of the clip. This tongue from where joined with the portion 3 extends rearwardly and in-

wardly towards the jaw 6 for a distance equal to substantially half the length of the tongue as shown at 8 and from then on is of arcuate form as shown at 9, in 5 order that said arcuate portion will engage and conform to the pencil. The portions 8 and 9 define a locking shoulder 10 which yieldingly engages the pencil so as to prevent an unintentional lateral movement of 10 the pencil out of the holder.

The grip provided is sufficient to hold the pencil against dropping out of the holder but as above stated, permits of a free withdrawal of the pencil directly upwardly 15 out of the holder. Due to the spring tongue 7 for locking the pencil in place and against being moved laterally out through the clip, it is possible to provide a light, strong clip which is not subject to being 20 easily deranged or bent out of shape. By provision of the spring tongue 7, the outer member of the U-shaped clip formed by bending the member 3 as described, need not be bent out of straight line extending 25 substantially parallel to the opposed faces of the jaw 6 and member 2.

Although the spring tongue permits the pencil to be readily inserted laterally into the clip, it acts as a lock to prevent lateral movement of the pencil out of the clip. 30 This is essential in that when the pencil is

held in the clip it is subject to being accidentally engaged such as would cause it to be moved laterally out of the clip.

I claim:

1. A pencil holder comprising opposed resilient jaws adapted to clamp between them the outer wall of a garment pocket, a laterally opening clip on one of the jaws in which clip a pencil may be moved sideways in the lateral opening therein in a position to be removably held, a resilient tongue carried by said clip adapted to yieldingly clip a pencil between it and one side of the clip, and a shoulder provided intermediate of the ends of the tongue permitting insertion of a pencil between the clip and the tongue but preventing lateral withdrawal of the pencil past the shoulder. 40

2. A pencil holder comprising opposed spring jaws adapted to clamp between them the outer wall of a garment pocket on which the holder is mounted, a laterally opening clip on one of the jaws into which clip a pencil is removable sidewise through the 55 lateral opening and a resilient tongue carried by said clip extending first outwardly and rearwardly from one side of the clip towards the other side and then being bent for the remainder of its length into an arcuate form. 60

WILLIAM J. WHITE.
